UNITED STATES PATENT OFFICE.

ARTHUR D. MANSON, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BURNISHING TOOL.

Application filed April 19, 1920. Serial No. 374,968.

To all whom it may concern:

Be it known that I, ARTHUR D. MANSON, a citizen of the United States, residing at Lynn, in the county of Essex and State of Massachusetts, have invented certain Improvements in Burnishing Tools, of which the following description, in connection with the accompanying drawings, is a specification, like reference characters on the drawings indicating like parts in the several figures.

This invention relates to shoe finishing machines, and is herein described as embodied in a machine for burnishing the contour surfaces of heels of boots and shoes.

A type of machine commonly used for this purpose is provided with a rotary finishing tool having a working face made up of a series of diagonally disposed, yieldingly mounted, burnishing elements arranged to follow each other successively over the heel surface operated upon. The yielding mounting of these diagonally disposed members is depended upon only to treat the minor irregularities of the heels operated upon, the tool as a whole, up to the time of the present invention, having been made to conform to the exact height, pitch and contour of the back of the heel on which it was intended to operate. While such finishing tools are highly effective for operating upon the particular heels for which they respectively are designed, they have the disadvantage that a considerable number of different tools must be kept on hand to finish the different styles of heels made. Moreover, since a different tool must be used for each different kind of heel, there is a considerable loss of time due to the necessity of changing the tool when the operative passes from one form of heel to another.

It is an object of the present invention, accordingly, to provide a heel finishing tool which shall be substantially universal in that it may be effectively utilized to finish heels of the different types or styles in ordinary use, including Louis heels of varying forms, the so-called "straight" heels used on women's shoes, such as Cuban and military heels, and others, as well, of course, as the ordinary run of heels used on men's and children's shoes. This may be accom-

plished by making a portion of the finishing tool of such a shape as is appropriate to the finishing of "straight" and the upper portion of Louis heels, and an adjoining portion of a progressively varying curvature, different parts of which may be selected to fit the curvature of the lower part of different styles and shapes of Louis heels.

In the illustrated embodiment of the invention the fore part of the tool is of a substantially, but not necessarily exactly, conical form, and the rear portion is in the form of a conoid with its radial section of a progressively increasing radius of curvature, passing from approximately the position of maximum diameter toward the rear. Otherwise expressed, the illustrated tool, considered as a whole, may be said to have the form of a conoid generated by the rotation about a fixed axis of a line, one portion of which is straight or of a very slight curvature, and another portion of which, adjacent to the termination of the substantially straight portion, is curved with a progressively increasing radius of curvature. With a tool so formed, a "straight" heel or the upper part of a Louis heel can be finished on the forward portion of the tool, while the lower part of a Louis heel can be finished on the rear portion of the tool. Moreover, owing to the variation in the curvature of the rear portion of the tool, Louis heels of widely different dimensions and curvature may be finished with the same tool, it being necessary only to select and utilize that portion of the tool which corresponds to the curvature of the particular heel to be finished.

A feature of the illustrated embodiment of the invention lies in the making of the tool of such form that the diameters at the front and rear ends of the tool are approximately equal. This has at least two desirable results. First, the difference between the maximum and minimum diameters is reduced to a minimum, and, as a consequence the tendency of molten wax used with the tool to collect on the portion of maximum diameter, and hence to spatter off and to be unevenly applied to the work, is reduced to a minimum; and second, in operating upon women's shoes with the usual types of heels the shoe may be held at

all times with its longitudinal axis at right angles to the tool shaft or inclined rearwardly therefrom, instead of inclined forwardly therefrom as has previously been the practice. Since finishing machines having tools of this type are commonly provided with other tools, for instance with covered pad brushes and with finishing brushes, located to the rear of the burnishing tool, this reduces the distance through which the shoe must be moved in presenting it to the different tools, thus reducing the strain upon the operative and correspondingly increasing the output.

With these and other objects and features in view, the invention will now be described as embodied in an illustrative machine and pointed out in appended claims.

In the accompanying drawings,

Figs. 1 and 2 are plan views of the finishing tool of the present invention, showing a shoe with its heel in such relation thereto as to illustrate the finishing of the upper and lower portions, respectively, of a Louis heel;

Fig. 3 is a similar diagram illustrating the finishing of a "straight" heel; and

Fig. 4 is a diagrammatic plan view of a machine in which this tool may be embodied and showing its relation to other tools of the machine.

The tool 8 of the present invention is made up of a series of diagonally disposed burnishing elements 10 independently supported, as through projections 12 formed on their under sides, by leaf springs 14 secured at one end to a hub member 16 and capable of limited movement at their other ends. Tools of this character are well-known and are in general use at the present time and it is therefore considered unnecessary to describe in further detail the construction thereof. It should be noted, however, that the showing of the drawings is intended to be exemplary and to be taken in an illustrative sense, and that the tool of the present invention is in no way limited to one having its elements supported as shown.

The burnishing tool of the present invention is formed, as clearly shown in the Figures of the drawings, with its forward portion 30 substantially conical so as to conform substantially to the upper portion of a Louis heel or to the entire contour surface of a so-called "straight" heel. Since, however, the so-called "straight" heels actually are usually made with a slight curvature, it is desirable to depart somewhat from a true cone in shaping the forward portion of the tool and to give a slight bulge to the curvature thereof. The rear portion 32 of the tool is formed of a comparatively sharp curvature but with a gradually increasing radius of curvature passing rearwardly

from approximately the position of maximum diameter. Thus the tool is so shaped that a portion thereof towards the rear may be found to fit the curvature of the lower part of any Louis heel. In burnishing a "straight" heel with this tool it is necessary only to move the shoe so that the different parts of the contour surface of the heel are presented to the tool in the usual manner. In burnishing a Louis heel however, it is necessary to make two passes of the shoe at the tool, the first burnishing the upper portion of the heel and the second the lower portion, the longitudinal axis of the shoe being rotated in the plane of the axis of the tool between the two passes so as to bring the lower portion of the heel into contact with the appropriate part of the tool.

In Figs. 1, 2 and 3 the heel is illustrated in a position slightly removed from the burnishing tool so that the edge of the heel and the edge of the tool may be indicated by separate lines and their relation more clearly shown. In the actual use of the tool of course, the heel is pressed firmly in contact therewith, hot wax, if desired, being applied to the heel in the usual way.

In Figs. 4 the burnishing tool as a whole is shown as carried by a shaft 18 suitably supported by a frame 20, the latter carrying also suitable bearings for a shaft 22, the two shafts being illustrated as parallel. The shaft 22 may carry appropriate tools, for instance a beading tool 24, a padded brush 26 and a finishing brush 28. The two shafts are driven at high speed by any appropriate means.

It will be apparent from Fig. 4 that the shoe the heel of which has been burnished by the tool 8 is in position conveniently to be transferred rearwardly to the other finishing tools and that the operative may do this with greater facility than would be the case if the tool 8 were of such pitch that the shoe was inclined forwardly to the left and so, considered as a whole, was at a greater distance from the other tools.

Having described my invention, what I claim as new and desire to secure by Letters Patent of the United States is:

1. A rotary heel finishing tool made up of a series of relatively movable finishing elements each having its front and rear portions of substantially the same diameter and its median portion of a greater diameter than its front and rear portions, said tool being constructed and arranged thereby to generate a work engaging surface adapted to treat one part of a heel at one side of the greater diameter and a surface adapted to treat another part of a heel at the other side of said diameter.

2. A rotary heel finishing tool comprising a carrier yieldingly sustaining a series of independently supported, diagonally dis-

- posed, finishing members, arranged to follow each other successively over the heel surface operated upon, the front and rear diameters of the tool as a whole being substantially equal, and the section of greater diameter of the tool disposed therebetween, said tool being constructed and arranged so that pieces of work of markedly different character may be applied to the surfaces at either side of the section of greater diameter and clearance left between the work and the part of the tool not being used. 5
3. A rotary heel finishing tool having a portion of its surface of a conoidal form with the periphery of its radial longitudinal section having a median point of maximum diameter and constructed with a radius of curvature progressively increasing from the maximum diameter to one end. 10
- 20 4. A rotary heel finishing tool having a portion of conical shape to conform to the contour surface of straight heels or to the upper portion of Louis heels, and an adjoining portion of a progressively varying curvature different portions of which may be selected to conform to the curvature of the lower part of different styles and shapes of Louis heels. 15
5. A rotary heel finishing tool having its forward portion of a substantially conical form and its rear portion of a conoidal form with the periphery of its radial section of a progressively increasing radius of curvature, passing from approximately the posi- 25
- tion of maximum diameter of the tool toward the rear. 35
6. A rotary heel finishing tool having the form of a conoid generated by the rotation about a fixed axis of a line one portion of which is substantially straight, and another portion of which, adjacent to the termination of said substantially straight portion, is curved with a progressively increasing radius of curvature. 40
7. A rotary heel finishing tool having the form of a conoid generated by the rotation about a fixed axis of a line a portion of which is a curve of large radius corresponding to the slight curvature of a so-called "straight" heel, and another portion of which adjacent to the termination of said first named portion is curved with a less but progressively increasing radius of curvature. 45
8. A rotary heel finishing tool having a working face comprising two differently formed work engaging surfaces, one surface constructed and arranged to finish a certain portion of a heel and the other surface constructed and arranged to finish a different portion of the heel, said surfaces meeting near the maximum diameter of the tool as a whole thereby leaving clearance for that part of the heel not being treated. 50
- In testimony whereof I have signed my name to this specification. 55

ARTHUR D. MANSON.
